UNITED STATES PATENT OFFICE.

CHARLES A. STATLER, OF CHICAGO, ILLINOIS.

ROOF.

1,338,262.

Specification of Letters Patent. Patented Apr. 27, 1920.

Original application filed March 29, 1918, Serial No. 225,403. Divided and this application filed April 5, 1919. Serial No. 287,730.

To all whom it may concern:

Be it known that I, CHARLES A. STATLER, a citizen of the United States, residing at Chicago, in the county of Cook and State of Illinois, have invented a certain new and useful Improvement in Roofs, of which the following is a full, clear, concise, and exact description, reference being had to the accompanying drawings, forming a part of this specification.

My invention relates to improvements in roofs, and has special reference to improvements in the construction of roof gutters.

In the covering of roofs with flexible material made of a base material such as jute impregnated with asphaltum and covered with grit, it has been common practice heretofore to form the gutter of the roof of metal, with flashings running up beneath the lower edge of the flexible roofing material on the roof. This form of construction requires the presence on the job of the sheet metal worker as well as the roofers and the construction is expensive. In the first place, it is the part of the roof which deteriorates most rapidly, and is the first to need repair.

I have conceived the idea of forming the gutter, as well as the roof proper, of the flexible roofing material, of forming it in such a manner that but slight additional expense is necessary to form the foundation for the gutter, and in such construction to carry out and preserve the idea of fully covering and protecting all nails and fasteners by the durable, flexible roofing material, which idea was first disclosed in my pending application on roofs, filed March 29, 1918, Serial Number 225,403, and of which this present application is a division.

By means of my invention I am enabled to eliminate all sheet metal work about roofs, except possibly the down spout; I am enabled to provide a gutter which is just as durable as the roof itself, which does not require frequent painting or renewal and which in fact once installed, is substantially permanent.

I am enabled to produce a gutter with much less expenditure, of time, labor and material, in other words, I am enabled to produce a gutter which is more durable and less expensive than the metallic gutters heretofore used. Furthermore, by means of my invention, I am enabled to produce a gutter which is so arranged that it catches and drains away all of the water which falls

upon the roof, as my gutter is arranged at the extreme lower edge thereof. At the same time the finished roof is much more sightly and durable than those equipped with hanging gutters.

My invention will be more readily understood by reference to said drawings, in which:

Figure 1 is a perspective view of a roof provided with a gutter made in accordance with my invention;

Fig. 2 is a fragmentary vertical sectional view of the lower edge of the roof on the line 2—2 of Fig. 1;

Fig. 3 is a sectional view similar to Fig. 2 particularly illustrating the manner of making the gutter;

Fig. 4 is a view similar to Fig. 2, showing a modified form of construction; and

Fig. 5 is an enlarged fragmentary sectional view of the material which I preferably use in forming my improved gutter.

My present invention is related closely to a roof construction wherein the roof proper is covered with horizontally extending strips 1, of flexible roofing material made up of flexible webbing impregnated and covered with asphaltum and preferably covered on its weather surface with colored grit or sand embedded in the asphaltum, and by means of which the roofing sheets are given any color desired, and is particularly adapted to simulate a tile roof.

The sheets or strips 1 are secured to and upon the roof, with their adjacent horizontal edges in overlapping sealed relation, and my present invention has to do particularly with the lower or gutter edge of the roof thus formed.

In making the roof proper, I preferably provide a roof edge or facing board 2 arranged vertically at the lower edge of the roof, and suitably fastened to the lower edge of the roofing boards.

I arrange this facing board longitudinally along the edge of the roof and with its upper edge projecting above the adjacent surface of the roof, so as to provide a triangular space 3 between the board and the adjacent lower part of the roof. It will now be evident that if I line this triangular space so as to make it water tight, I will have a gutter to drain the water from the roof, and that I will be able to catch all the water that falls upon the roof.

For forming the water tight lining for

this space, and thus providing a gutter, I take a strip 4 of the flexible roofing material, and I secure one longitudinal edge of the strip upon the upper part of the facing board 2. I secure it to the facing board by means of a clamping strip, rod or bar 5, which may have the form of a round rod as shown, to permit the sheet 4 to be formed around same, and reduce the liability of the sheet to crack or fracture in this process. I secure this clamping bar and the edge of the sheet 4 by nails 6 which I drive down through the rod and the edge of the sheet and into the upper edge of the facing board 15 2. In placing the sheet, to be thus fastened at its outer edge, I arrange it in the position shown in Fig. 3, with its grit or weather surface 7 on the inside or toward the board 2.

Having secured the edge of the strip, as shown in Fig. 3, I turn the whole strip over and upon the roof and form it down into the gutter space to form a gutter 8, as shown in Fig. 2, the free edges of the sheet extending up upon the roof 9. In 25 thus turning the sheet over I cover the rod 4 and the nails 6 with the flexible roofing sheet, thus effectually sealing these parts against deterioration by the weather. The sheet 4 being flexible, it can very readily 30 be formed down into the triangular space, and I preferably do this by means of a forming member similar to a narrow board which I place within the turned down or turned over sheet and by standing upon the 35 board press the sheet down closely into the triangular space against the outer board 2 and against the surface of the roof. The sheet 4 lies flat upon the upper surface of the roof and forms the lower part of the 40 roof covering, the lower edge of the first roofing strip 1 being secured upon the roof at the upper edge of the strip 4 in overlapped relation thereto, and preferably 45 clamped thereto by means of a clamping rod or member 10, and nails 11, as shown in Fig. 2.

In Fig. 4 I have illustrated a modified form of the gutter. In this form I secure the first edge of the gutter sheet 4 to the outer surface of the board 2 instead of to its top edge, by means of a wooden strip 12 and nails 13 and then I turn the sheet 4 over as in the first instance, to form the gutter. In this form also the clamping strip 12 55 and the nails 13 which secure the first edge of the sheet are covered and protected from the weather.

The gutter thus formed at the lower edge of the roof drains into the down spout 13, 60 generally arranged as shown at one corner of the building.

As shown in Fig. 5 I preferably use a roofing material, which consists of a base or foundation of wool felt, or some similar fibrous material 14. This base is impreg-

nated with a water proofing material such as asphaltum, and the lower surface may be covered with a paper sheet 15, to prevent the strip of roofing material sticking together when rolled up for shipping. The 70 top or weather surface is usually provided with a layer 16 of asphaltum, in which is embedded and secured a coating or covering 17, of grit or sand. This grit coating may be made of any color to suit the conditions, 75 and it may be of the same color as the strips 1, although I frequently make it of a suitable contrasting color.

It will now be evident that by means of my invention I am enabled to form a gutter 80 of the same flexible material of which the roof itself is formed, that I am enabled to form the gutter in place quickly and easily and at low cost, and that by means of my invention I am enabled to cover and protect 85 all of the fasteners and fastening devices from the weather by means of the substantially indestructible roofing material of which I form the gutter.

I claim:

1. In a roof of the character described, an upstanding member at the lower edge of the roof providing a gutter space, a strip of flexible roofing material having a weather surface composed mainly of asphaltum or 95 the like, one edge of the sheet secured to the upper part of the upstanding member with its weather face in contact therewith, a clamping strip tightly securing the edge of the sheet to and against the upstanding member, whereby the asphaltum coating effects a weather tight seal between the sheet and the upstanding member, the body of said sheet formed over the clamping strip and down into the gutter space, and the opposite edge of the sheet extending up on the 100 roof and sealed thereto.

2. In a roof of the character described, an upstanding member at the lower edge of the roof providing a gutter space, a sheet of 110 flexible roofing material having a weather surface composed mainly of asphaltum or the like and having grit thereon, one edge of the sheet secured to the upper edge of the upstanding member with its weather 115 surface in contact therewith, a clamping strip tightly securing the edge of the roofing sheet to the upper edge of the upstanding member, the asphaltum or the like being sufficient to effect a tightly sealed joint between the roofing sheet and the upstanding member, the body of the roofing sheet being turned over the clamping strip and formed down into the gutter space, the clamping strip presenting a smooth rounded surface 120 without projecting edges to the roofing sheet.

In witness whereof I hereunto subscribe my name this 2nd day of April 1919.

CHARLES A. STATLER.
